(57) **CLAIM**

The ornamental design for a toothbrush with stand and removable brush head, as shown and described.

DESCRIPTION

FIG. 1 is a perspective view of the toothbrush with stand and removable brush head.

FIG. 2 is a perspective view of the toothbrush with stand and removable brush head with broken lines illustrating the brush head in an elevated position being removed from the body of the toothbrush.

FIG. 3 is a left side elevational view thereof, the right side view being a mirror image of the left side view.

FIG. 4 is a front elevational view thereof.

FIG. 5 is a rear elevational view thereof.

FIG. 6 is a top plan view thereof; and,

FIG. 7 is a bottom plan view thereof.
